UNITED STATES PATENT OFFICE.

ISRAEL HOGELAND, OF INDIANAPOLIS, ASSIGNOR TO HIMSELF, THOMAS E. PHILLIPS, OF SAME PLACE, AND CHARLES ORME, OF MARION COUNTY, INDIANA.

IMPROVEMENT IN THE MANUFACTURE OF BUCKETS.

Specification forming part of Letters Patent No. **179,655**, dated July 11, 1876; application filed March 7, 1876.

To all whom it may concern:

Be it known that I, ISRAEL HOGELAND, of Indianapolis, county of Marion, State of Indiana, have invented an Improvement in the Manufacture of Buckets, of which the following is a description, reference being had to the accompanying drawings.

My invention consists in the arrangement of saws on a mandrel, guides on the table for the wood, cone feed-rollers, to feed the blank onto the saws, and pressure-rollers, to hold the blank onto the chine-grooving saw, as more fully set forth in the annexed claims.

Figure 1 represents a plan view of my improved bucket-machine. Fig. 2 is a sectional view of the same. Fig. 3 represents the stave complete. Fig. 4 is an end view of Fig. 3. Fig. 5 represents the bucket as formed by my improved machine.

C represents the table-top, mounted on any ordinary frame-work, to which is secured the saw-mandrel P by suitable boxes R R¹ R². On the mandrel P, at its outer end, is secured the driving-pulley P', and between the boxes R¹ and R² are secured, as shown, the two outside dished saws L L¹, with the small grooving dished saw L² located at the proper distance from saw L to cut the groove *a* in the stave for the bottom of the bucket to be secured in. On the top of the table C are arranged curved guides E K K'. The guide E is set far enough back to allow the corners of the blank A' to engage with it, as shown, so as to allow the saws L L¹ to cut out the segment embraced between the dotted lines *b b'* of the blank A'. The curved guides K K' are arranged on the table opposite the curved guide E, and their inner faces are designed to be on a line with the dished saws L L¹, so as to receive and guide the segment A while the saws L L¹ are cutting, and to guide said segment after the blank A' has left the feed-rollers F.

The feed-roller F is made cone-shaped, and is covered with rubber, and the boxes H H', in which the feed-roller shaft G operates, are arranged so that the shaft G radiates from the common center of the curved guides

E K K'; and the rear box H' is elevated sufficiently above the box H to allow the lower edge of the cone feed-roller F to lie flat with the table. Immediately under the feed-roller F is another roller, secured in the table, and the blank A' is fed to the saws between the feed-roller F and the roller under it. The feed-roller F is operated by the pulley J, as shown.

The bar D is secured to the table in front, as shown in Fig. 1, and more fully in Fig. 2, and its inner end is elevated, so as to pass over the dished saw L; and on the end of the bar D is journaled the pressure-wheel O, which is designed to hold the segment-stave A down onto the grooving-saw L², as shown in Fig. 2; and to prevent the segment-stave A from sticking, or hindering the feed-roller F from forcing the segment through, I employ a small frictional roller, S, embedded in the table immediately under the pressure-roller O, as shown.

To operate my improved machine, power is applied to the pulleys P' and J, and, as the saws L L¹ L² and feed-roller F revolve, the blanks A' are fed to the saw, as shown in Fig. 1. The feed-roller F forces the blank A' onto the saws, and the segment A is formed with the groove *a*, as shown in Figs. 3 and 4, after which the segment-staves A are jointed and sized, and, when trussed up and hooped with the bottom in, forms a bucket of one stave, as shown in Fig. 5.

By the addition of an extra grooving-saw, L², to form a groove at the other end of the stave, I can make mackerel-kits with heads at both ends.

What I claim as new, and wish to secure by Letters Patent, is—

1. In a machine for the manufacture of buckets, &c., the combination of the saws L L¹ L², mandrel P, feed-roller F, mandrel G, boxes H H', and curved guides E K K', in the manner shown, for the purposes set forth and described.

2. The feed-roller F, formed cone-shaped, and provided with a rubber tube, in the manner shown, and arranged to operate in the boxes H H', the rear box being elevated, so as

to allow the lower edge of the cone feed-roller F to lie parallel with the table, for the purposes set forth and described.

3. In a bucket-machine, the combination of the pressure-bar D and roller O, arranged and adapted to be operated in connection with the stave A and small roller S, in the manner shown, for the purposes set forth and described.

In testimony whereof I have signed my name to this specification in the presence of two subscribing witnesses.

ISRAEL HOGELAND.
